CLAIM

The ornamental design for a head light for a motorcycle, as shown and described.

DESCRIPTION

FIG. 1 is a front elevational view of a head light for a motorcycle showing my new design;

FIG. 2 is a left side elevational view thereof;

FIG. 3 is a right side elevational view thereof;

FIG. 4 is a top plan view thereof; and,

FIG. 5 is a bottom plan view thereof.

The broken line showing of the environment is for illustrative purposes only and forms no part of the claimed designs. The portion encompassed by a solid line is the design sought to be patented.
